UNITED STATES PATENT OFFICE.

ROGER W. BABSON, OF WELLESLEY HILLS, MASSACHUSETTS.

TYPE-WRITER KEY-STRIKER OR HAND EXTENSION.

1,242,307.

Specification of Letters Patent.

Patented Oct. 9, 1917.

Application filed December 18, 1915. Serial No. 67,570.

To all whom it may concern:

Be it known that I, ROGER W. BABSON, a citizen of the United States, residing at Wellesley Hills, in the county of Norfolk and State of Massachusetts, have invented new and useful Improvements in Type-Writer Key-Strikers or Hand Extensions, of which the following is a specification.

This invention has for its chief object to 10 provide a device or hand extension whereby a typewriter operator or typist may selectively manipulate the keys of a typewriter while wearing mittens and working in a so-called "out-door" office.

15 Another object of the invention is to enable a typist to manipulate the typewriter keys while the elbows are supported by chair arms, thus minimizing fatigue attending the operation.

20 The invention is embodied in a key striker or hand extension comprising an elongated rod formed at its inner end portion as a hand grip adapted to be grasped by a mittened hand, and a finger located at the outer end 25 of the rod and arranged at an angle thereto, said finger having a striking peen formed to coöperate with the blow-receiving face of a typewriter key button in depressing the key.

30 The length of the rod is such that when its grip portion is grasped by the operator's hand, the finger is sufficiently projected from the hand to enable the peen to be applied to either of a plurality of buttons by 35 wrist flexure alone and without movement of the elbow, which may therefore rest on a chair-arm during the operation.

The button face usually has an annular raised ridge surrounding a depressed central portion.

Owing to the fact that the operator's hand is at a distance from the button when depressing the key through the hand extension of my invention, there is liable to be 45 some aberration of the peen, preventing it from striking the button face centrally. To compensate for this aberration I form the peen so that it is automatically centralized by the raised rim of the button in case the 50 peen is out of center when it first strikes the button.

The object of thus centralizing the hammer head relatively to the button is to prevent liability of depressing more than one 55 button, which liability might exist if the peen in descending on the selected button is

so far out of center that, if not thus centralized, it would encroach on the space occupied by another button of the same row, the buttons being closely spaced. 60

To prevent wear of the button and liability of injury thereto, particularly when it has a glass cover on its central portion, I preferably make the peen of relatively soft compressible material, which also deadens 65 the sound, cushions the blow, and minimizes the jar on the operator's hand.

Of the accompanying drawings forming a part of this specification:

Figure 1 represents a side elevation of a 70 hand extension embodying my invention;

Fig. 2 represents a view of the under side of the extension;

Fig. 3 represents a section on line 3—3 of Fig. 2; 75

Fig. 4 represents a side elevation of a differently constructed extension embodying the invention.

The same reference characters indicate the same or similar parts in all the views. 80

In the embodiment of the invention shown by Figs. 1, 2 and 3, 12 represents an elongated rod formed at its inner end portion as a hand grip, and 13 represents a finger on the outer end of the rod and arranged at an angle thereto, said finger having a striking peen 14. Any suitable and preferably rigid material may be employed in the construction of the rod. As here shown, the finger is integral with the rod. 90

The peen 14 is formed to engage and depress a single key button 15, as indicated by Figs. 1 and 3. Preferably the peen is formed to be deflected by the raised rim of the button 15 toward the center of the button in case of a slight aberration of the finger from its proper path when it is descending upon the button.

To this end the striking face of the peen may be made of convex form, as shown, the 100 diameter of the base portion of the peen being preferably considerably less than that of the button, so that the centralized peen does not overhang the margin of the button.

The peen may be made of rubber, cork, 105 felt, or other suitably soft compressible material adapted to minimize wear of the button, and prevent liability of breaking the face of the button when said face is made of glass. The compressibility of the peen also 110 cushions the blow and reduces noise and the jar on the operator's hand. The material of

the peen should be such that it will be free from liability to slip or glance too freely on the button.

As shown by Fig. 3, the peen is substantially hemispherical, its flat inner face being cemented or otherwise secured to the flat end face of the rigid body of the finger.

I have demonstrated the fact that an operator wearing mittens and holding one of the described hand extensions in each hand is able to operate a typewriter with satisfactory rapidity.

The hand extension is adapted to coöperate with a button having a flat central face surrounded by a raised rim, as indicated by dotted lines in Fig. 1, or with a button the face of which is concave or dished, as indicated by dotted lines in Fig. 3.

When the extension is held by a mittened hand I prefer to provide the inner end portion of the rod with a cover 17 of compressible frictional material, such as rubber, constituting a frictional hand grip preventing the rod from slipping and turning in contact with the mitten. Said cover may be a rubber tube removably applied to the rod.

The length of the extension as a whole is such that the finger 13 projects sufficiently from the operator's hand to enable the finger to be moved along a row of buttons by wrist flexure only, and without movement of the forearm and elbow. Consequently the operator may conveniently occupy a chair having arms which support the elbows and forearm, and therefore minimize fatigue to the operator.

This function of the extension is useful whether the operator's hands are mittened or bare.

When the extension is intended to be held by a bare hand the rod may be made of vitreous material, such as glass, as indicated by Fig. 4, in which the rod is designated by 12^a.

The finger 13^a and its peen 14^a may be made of a single body of rubber apertured to receive the outer end of the rod. A vitreous rod is easily kept clean and sanitary, and is believed to be useful in preventing neuritis.

Having described my invention, I claim:

1. A typewriter key striker comprising a rod of rigid material forming a hand grip and provided at one end with a laterally disposed finger having a striking peen shaped to engage a single typewriter key, said rod and said finger being of sufficient body to depress said typewriter key without flexing.

2. A typewriter key striker comprising a rod of rigid material forming a hand grip and provided at one end with a laterally disposed finger having a striking peen shaped to engage a single typewriter key, said rod and said finger being of sufficient body to depress said typewriter key without flexing, and a cover of frictional material upon the hand grip portion of said rod.

In testimony whereof I have affixed my signature.

ROGER W. BABSON.
